UNITED STATES PATENT OFFICE

2,626,130

HEAT EXCHANGER DEVICE

Leon Raskin, Brooklyn, N. Y.

Application August 19, 1949, Serial No. 111,131

2 Claims. (Cl. 257—256)

1

The present invention relates generally to heat exchangers and is concerned more particularly with an improved cold plate or evaporator plate for refrigerated cabinets such as are commonly employed in soda fountains and cabinets for the storage of ice cream, beverages, frozen foods and the like. The invention is also suitable as panel heaters, base board heaters, radiant heaters and for heating buildings as well as for heating fluids in industrial processes.

It is a general object of the invention to provide a heat exchanger or evaporator plate which is constructed and arranged in such a manner as to be characterized by a reduced pressure drop between the inlet and the outlet end thereof, thereby resulting in enhanced heat exchange and enhanced efficiency.

A particular object of the invention is the provision of an evaporator plate having an expansion chamber comprising a sinuous refrigerant passageway wherein certain of the bends or convolutions thereof are subdivided by means of parallel ducts in a novel manner insuring reduced friction to the flow of fluids, minimum expenditure of energy in conveying the heat exchange medium from one group of ducts to the next and a complete flooding of the refrigerant passageway.

Another object of the invention is the provision of a heat exchange evaporator plate of the character indicated which may be readily and inexpensively fabricated in a variety of shapes such as a flat plate, a U-shaped structure, an L-shaped structure, a boxlike structure, a cylindrical structure or the like.

The foregoing objects as well as additional objects and advantages of the invention will be readily apparent in the course of the following detailed description taken in connection with the accompanying drawing which illustrates preferred embodiments of the invention, and wherein:

Fig. 1 is a front elevational view of an evaporator plate embodying the features of the invention;

Fig. 2 is a front elevational view of a modified form of evaporator plate;

Fig. 3 is a fragmentary sectional view taken along line 3—3 of Fig. 1; and

Fig. 4 is a perspective view of an additional modification of the invention.

Referring first to Figs. 1 and 3 the evaporator plate, which is generally designated by reference numeral 10, comprises a pair of superposed metal sheets 11 and 12 which are preferably, but not

necessarily, rectangular in shape. One or both of said sheets is embossed, stamped or processed in any other suitable manner to define a continuous sinuous convolution or corrugation 13. 5 In the embodiments of the invention illustrated in the drawings, sheet 11 is shown as being formed with the sinuous corrugation 13 while sheet 12 is flat. The contiguous portions of sheets 11 and 12 between corrugation 13 and along the edges 10 of the sheet are secured together in any suitable manner as by seam welding or spot welding (not shown) so that the sinuous corrugation 13 defines a leakproof continuous passageway for the refrigerant. Said passageway serves as an expansion chamber for the refrigerant passing through the evaporator plate 10 and the particular advantages and special characteristics of the passageway which serve combinedly to achieve the objects of the invention will be described more fully hereinafter.

As may be seen in Fig. 1, the refrigerating medium such as sulphur dioxide, isobutane, methyl chloride, ammonia, Freon, etc. enters refrigerant passageway 13 through inlet duct 14 whereupon 25 it will be divided into two streams passing through the parallel ducts 15. It will be noted that the area of the refrigerant passageway 13 between inlet duct 14 and the parallel ducts 15 is reinforced by means of a spot welded, preferably circular indentation 16 in order to prevent distortion and expansion of the metal due to excessive internal pressure. As may be seen in the drawings and as will appear hereinafter, the remaining bights or bends of the refrigerant 30 passageway are also provided with indentations 35 16 for a similar purpose.

The refrigerating medium passes through the initial parallel ducts 15 to the first bight 17, thence around the indentations 16 and into a successive pair of parallel ducts 18, thence through the bight 19 and into a third pair of parallel ducts 20, thence through the bight 21 and through 45 a fourth pair of parallel ducts 22 and finally through the outlet duct 23. It will be noted that the bights or bends connecting the parallel ducts are arranged and constructed in such a manner as to offer a minimum resistance to the flow of refrigerant therethrough. Consequently there will be a minimum waste of energy in conveying the 50 refrigerant from one group of parallel ducts to the next. At the same time the provision of the sinuous passageway assures a reduction of friction as well as complete flooding of a maximum area of the evaporator plate. Sheets 11 and 12 are preferably seam welded between their parallel

ducts and spot welded at their bight portions to define the spaced parallel indentations 16.

Fig. 2 illustrates a modified form of evaporator plate having a somewhat different design and increased capacity over the modification initially described. In this connection it will be understood that the number of parallel ducts in each convolution or the number of convolutions may be varied as desired and consistent with the exigencies of particular situations and conditions. The embodiment of Fig. 2 illustrates an evaporator plate 25 provided with an inlet opening 26 through which the refrigerating medium is introduced directly into the bight 27 and thence into the first group of three parallel ducts 28. The refrigerant then passes into the bight 29 and then into the second group of three parallel ducts 30. The remaining portion of the evaporator plate is flooded in a similar manner and the refrigerant finally passes through the outlet duct 31 from which it may be conducted to additional plates of the refrigerating system.

It will be further noted that the bight portions of evaporator plate 25 preferably have a cross-sectional area substantially the same or greater than the aggregate area of the three ducts 28 or 30 communicating with said bight portion. The indentations 32 formed in the bight portions serve similarly to the indentations 16 of the initial embodiment to prevent distortion or expansion of the bight portions of the refrigerant passageway due to excessive internal pressure. Said indentations may be formed by spot welding or by form pressing or some other method.

As has been previously pointed out, the evaporator elements of the present invention may be fabricated in a large variety of shapes and forms differing from the flat plate embodiments of Figs. 1 to 3. Fig. 4 illustrates a box-type evaporator element 35 constructed according to the principles of the present invention. The upstanding walls of the element 35 may be provided with a sinuous passageway 36 in the manner described for the initial embodiments and may then be shaped to the desired configuration. The bights or bends of the refrigerant passageway 36 are also reinforced by means of indentations 37 which may be spot welded to prevent expansion and distortion of the sheets forming the element 35. An inlet opening 38 and an outlet opening 39 are provided for the refrigerating medium.

Since certain modifications may be made in the device of the invention without departing from the scope thereof, it is intended that all matter contained in the foregoing specification and shown in the accompanying drawing be interpreted merely as illustrative and not in a limiting sense.

What is claimed is:

1. In an evaporator plate for refrigerating systems, a pair of superimposed metal sheets, at least one of said sheets being provided with a continuous sinuous depression extending through the area of said sheet, said depression having parallel leg portions with intervening bight portions, 10 said leg portions being subdivided into a plurality of spaced parallel ducts terminating in said bight portions, each of said bight portions having a cross-sectional area not less than the aggregate area of the ducts in each of said leg portions, 15 said sheets having a longitudinal continuous depression intermediate said parallel ducts, said bight portions being each provided with a plurality of substantially circular indentations at spaced points between the ducts to form a series of intercommunicating passageways in communication with the several ducts, each of the said indentations having a diameter approximately equal to the width of each of the ducts.
2. In an evaporator plate as provided for in claim 1, wherein the substantially circular indentations are spaced apart a distance substantially equal to the width of each of the ducts, and said indentations are each in alignment with spaces between the ducts.
